ABSTRACT

A garment that is configured to attach to a bikini bottom is provided. The garment includes a band that is configured to be worn by a user. The band has a generally uniform circumference and includes a top portion, a bottom portion, and at least one attachment device that is configured to releasably attach the bottom portion to the top portion for securing the band to the bikini bottom when the bottom portion is received through at least one leg opening of the bikini bottom.

FIG. 1

FIG. 3

FIG. 2

FIG. 4

**GARMENT FOR LOOP ATTACHMENT
THROUGH LEG OPENINGS OF BIKINI
BOTTOM TO COVER MIDRIFT**

PRIORITY

The application is a continuation in part of application Ser. No. 15/087,229, which was filed with the U.S. Patent and Trademark Office on Mar. 31, 2016, the disclosure of which is incorporated herein by reference.

BACKGROUND

1. Field

The present disclosure relates to a garment, and more particularly, to a garment that is configured to attach to a bikini bottom to cover the midriff of a wearer thereof.

2. Description of the Related Art

Swimsuits typically come in two types, a one-piece type or a two-piece type, which is commonly referred to as a bikini. One one-piece bathing suits cover the pelvic area and a majority of the torso, while the bikini separately covers the pelvic area and upper torso, leaving the midriff bare.

While both types of swimsuits are suitable for their intended use, women who would otherwise opt to wear a bikini will sometimes opt for the one-piece bathing suit. For example, women who have scarring near their lower abdomen, e.g., as a result of a surgical procedure or being pregnant, may opt for the one-piece bathing suit as opposed to the bikini to hide their scarring.

U.S. Pat. No. 9,364,035 to Shachaf discloses a clothing trim that can be removably connected to a bottom edge of a clothing item via a fastening strip. Shachaf further discloses an extension trim that can be affixed to a bottom side of a clothing item, e.g., a skirt, shirt, or dress. However, Shachaf does not relate to swimwear. Moreover, the clothing and extension trims of Shachaf are merely attachable by a fastening strip, e.g., snaps, zippers, or buttons, and are not attachable through a leg opening of a bikini bottom.

U.S. Pat. No. 4,656,669 to Beard discloses a two-piece bathing suit with a hidden pocket in a panty section, with the pocket containing additional bathing suit materials to create an ensemble effect. However, like Shachaf, Beard is merely attachable by fastening strip, not through the leg opening of the bikini bottom.

SUMMARY

Embodiments of the present disclosure are described in detail with reference to the drawing figures wherein like reference numerals identify similar or identical elements.

In accordance with an aspect of the present disclosure, there is provided a garment that is configured to attach to a bikini bottom worn by a user, with the garment including a cylindrical band configured to be worn by the user, with the cylindrical band including a top portion, a bottom portion, and a pair of attachment devices that releasably attach the bottom portion to the top portion. The pair of attachment devices secure the cylindrical band to the bikini bottom by passing respective parts of the bottom portion through respective leg openings of the bikini bottom and releasably securing the respective parts of the bottom portion to opposite sides of the top portion.

In accordance with an aspect of the present disclosure, there is provided a method of extending coverage of a bikini bottom over a midriff by extending respective parts of a bottom portion of a garment downward through respective leg openings of the bikini bottom; folding a top portion of the garment downward onto the extended respective parts of the bottom portion; encircling the respective leg openings by attaching the respective parts of the bottom portion of the garment to corresponding parts of the top portion of the garment via a pair of attachment devices each having two parts, with each attachment device of the pair of attachment devices being positioned on a front of the garment, on opposite sides of a user's naval, in a wearing state.

15 BRIEF DESCRIPTION OF THE DRAWING

Various embodiments of the present disclosure are described hereinbelow with references to the drawings, wherein:

20 FIG. 1 illustrates a garment that is configured to be worn by a user to attach to a bikini bottom, with the garment shown unattached to the bikini bottom, according to an embodiment of the present disclosure;

25 FIG. 2 illustrates the garment of FIG. 1, with a bottom portion of the garment being received through a leg opening of the bikini bottom;

30 FIG. 3 illustrates the garment of FIG. 1 attached to the bikini bottom; and

35 FIG. 4 illustrates a garment according to another embodiment of the present disclosure.

DETAILED DESCRIPTION

Detailed embodiments of the present disclosure are disclosed herein; however, the disclosed embodiments are merely examples of the disclosure, which may be embodied in various forms. Therefore, specific structural and functional details disclosed herein are not to be interpreted as limiting, but merely as a basis for the claims and as a representative basis for teaching one skilled in the art to variously employ the present disclosure in virtually any appropriately detailed structure.

As noted above, a garment that is configured to attach to a bikini bottom may prove useful in the bathing suit industry, other than the shapewear industry, with such a garment being described herein.

45 FIG. 1 illustrates a garment **10** being worn by a user (e.g., a woman) before being removably attached to a bikini bottom **20**, i.e., with the garment **10** being shown unattached to the bikini bottom **20**, particularly a low waist bikini.

The garment **10**, i.e., midriff cover, is formed as a band having a generally cylindrical configuration, i.e., a cylindrical band configuration, with a top portion **12**, a bottom portion **14**, and a pair of attachment devices that releasably attach the bottom portion **14** to respective parts of the top portion **12**, to secure the garment **10** to the bikini bottom **20** when each attachment device of the bottom portion **14** is received through respective leg openings of the bikini bottom **20** (FIGS. 2 and 3) and attached to respective parts of the top portion **14**.

55 The pair of attachment devices includes apertures **16** that are located on respective sides of the top portion **12** of the garment **10**. A pair of buttons **18** are located at corresponding positions on the bottom portion **14** of the garment and configured to be received through the pair of apertures **16** when a user secures the garment **10** to the bikini bottom **20** by threading through the respective leg openings.

While the pair of buttons **18** and the pair of apertures **16** are shown provided on the bottom portion **14** and top portion **12**, respectively, the pair of buttons **18** can alternatively be provided on top portion **12** and the pair of apertures **16** can be provided on the bottom portion **14**.

The garment **10** can be made from any suitable material including, but not limited to, nylon, cotton, polyester, spandex, synthetic fiber having enhanced elasticity such as Lycra®, lace, elastane, blended synthetic fibers, polybutylene terephthalate, stretch fabric, other suitable material, or combination thereof.

In use, a user can slip the garment **10** around the user's midriff, as shown in FIG. 1. With the user wearing the bikini bottom **20**, the user pulls each side of the two sides of the bottom portion **14** of the garment **10** through a respective leg opening of the bikini bottom **20** (FIG. 2).

To secure the garment **10** to the bikini bottom **20**, the user folds the top portion **12** of the garment **10** over a waist portion **22** of the bikini bottom **20**, towards the bottom portion **14** of the garment **10**, and secure the top portion **12** to the bottom portion **14** by affixing each button **18** to a respective aperture **16**.

Coverage of a bikini bottom is extended over a midriff by extending respective parts of a bottom portion of a garment downward through respective leg openings of the bikini bottom; folding a top portion of the garment downward onto the extended respective parts of the bottom portion; encircling the respective leg openings by attaching the respective parts of the bottom portion of the garment to corresponding parts of the top portion of the garment via a pair of attachment that devices each have two parts, with each attachment device of the pair of attachment devices being positioned on a front of the garment, on opposite sides of a user's naval, in a wearing state.

From the foregoing and with reference to the various figure drawings, those skilled in the art will appreciate that certain modifications can also be made to the present disclosure without departing from the scope of the same. For example, other devices can be used for the attachment device **15**. More particularly, the buttons can be replaced with a string, to allow to fastening through being bikini bottoms that have a thicker waistband.

Moreover, the garment **10** can come in a variety of sizes and colors to accommodate a need of a user or a manufacturer. For example, a size of the garment **10** can correspond to a size of the user's midriff, to provide a vertical extension of the bikini bottom.

In certain instances, it may prove advantageous to provide the garment **10** with a top portion **12** that is configured to indirectly connect to the bottom portion **14**. For example, as noted above, the attachment mechanism may include string,

useful for high-waist bikinis. In this particular instance, a string **19** can be used to tie or wrap around the waist portion **22** of the bikini bottom **20** to attach the garment **10** to the bikini bottom **20**. For example, to attach the garment **10** to the bikini bottom **20**, the user can secure the bottom portion **14**, which includes the string **19** to extend the operable length of the buttons **18**, of the garment **10** to the waistline **22** of the bikini bottom **20** (see FIG. 4, for example); the string **19** can be looped through the leg opening of the bikini bottom **20**. After looping through the leg opening, an aglet **21** of the string can be affixed to apertures **16** to secure the garment **10** to the bikini bottom **20**.

A charm, pendant, or the like can be used to enhance the ornamentality of the aglet **21**.

While the garment **10** has been described herein as being used by women, men are also contemplated users, as the garment **10** can be configured to attach to a men's bathing suit, to provide a waste sash, e.g., cummerbund.

While several embodiments of the disclosure have been shown in the drawings, it is not intended that the disclosure be limited thereto, as it is intended that the disclosure be as broad in scope as the art will allow and that the specification be read likewise. Therefore, the above description should not be construed as limiting, but merely as exemplifications of particular embodiments. Those skilled in the art will envision other modifications within the scope and spirit of the claims appended hereto.

What is claimed:

1. A swimsuit comprising:

a bikini bottom having a waistband and leg openings; and a garment including a band configured to be worn around a waist, the band including:

a top portion having first attachment devices, and a bottom portion spaced from the top portion having second attachment devices, wherein the first attachment devices are adapted to engage the second attachment devices to secure the band in a folded banded configuration through leg openings of the bikini bottom,

wherein the garment is secured about the waistband of the bikini bottom through the leg openings of the bikini bottom by the first and second attachment devices.

2. The swimsuit of claim 1, the first attachment devices are buttons.

3. The swimsuit of claim 1, wherein the band is made from a material that is selected from a group consisting of nylon, cotton, polyester, spandex, and synthetic fiber.

4. The swimsuit of claim 1, wherein the garment is separable from the bikini bottom by uncoupling the first and second attachment devices.
